(57) **CLAIM**

We claim the ornamental design for a shoe care machine, as shown and described.

DESCRIPTION

FIG. 1 is a front perspective view of a shoe care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 2; and,

FIG. 10 is an exploded front perspective view thereof in which the shoe hanger is shown separated from the shoe care machine.

The broken lines in the figures depict portions of the shoe care machine which form no part of the claimed design.

The dot-dash broken lines encircling portions of the claimed design that are illustrated in enlargements form no part of the claimed design.
